DESIGN FOR A SPECTACLE FRAME OR THE LIKE

Edward M. Splaine, Southbridge, Mass., assignor
to American Optical Company, Southbridge,
Mass., a voluntary association of Massa-
chusetts

Application January 25, 1947, Serial No. 136,432

Term of patent 14 years

(Cl. D57—1)

To all whom it may concern:

Be it known that I, Edward M. Splaine, a citizen of the United States of America, residing at Southbridge, in the county of Worcester and State of Massachusetts, have invented a new, original, and ornamental Design for a Spectacle Frame or the Like, of which the following is a specification, reference being made to the accompanying drawings, forming a part thereof.

Fig. 1 is a front elevational view of a spectacle frame showing my new design; and

Fig. 2 is a top plan view of the spectacle frame shown in Fig. 1.

The characteristic features of my design are shown in full lines in the drawing.

I claim:

The ornamental design for a spectacle frame or the like, substantially as shown and described.

EDWARD M. SPLAINE.
